CARRYING CASE FOR A CAMERA

Arthur H. Crapsey, Jr., Rochester, and Richard J. Olson,
Lima, N.Y., assignors to Eastman Kodak Company,
Rochester, N.Y., a corporation of New Jersey

Filed Feb. 20, 1963, Ser. No. 73,659

Term of patent 14 years

(Cl. D61—1)

FIG. 2

FIG. 1

Des. 197,095

FIG.4

FIG. 5

FIG. 7

FIG. 6

FIG. 1 is a front elevational view of a carrying case for a camera showing our new design;

FIG. 2 is a top plan view thereof;

FIG. 3 is a rear elevational view thereof;

FIG. 4 is a bottom plan view thereof;

FIG. 5 is a right-side elevational view thereof;

FIG. 6 is a left-side elevational view thereof; and

FIG. 7 is a right-side elevational view thereof in open condition.

The outline of a camera is shown in broken lines in FIG. 7 for illustrative purposes only.

We claim:

The ornamental design for a carrying case for a camera, as shown and described.
